UNITED STATES PATENT OFFICE.

FRANK M. SLOUGH, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE SWITCHING SYSTEM.

1,324,750.

Specification of Letters Patent.

Patented Dec. 9, 1919.

Application filed August 12, 1918. Serial No. 249,501.

To all whom it may concern:

Be it known that I, FRANK M. SLOUGH, a citizen of the United States, residing at Rochester, Monroe county, State of New York, have invented certain new and useful Improvements in Telephone Switching Systems, of which the following is a specification.

My invention relates to improvements in telephone switching systems and has for its object the provision of a cheaply produced efficient means through which telephonic inter-connection may be accomplished between subscribers by the use of relays and apparatus auxiliary thereto, the relays referred to being preferably energized only when the connection is being established, the relay contacts being mechanically maintained in their operative positions in such a manner as to maintain the connection until the end of the conversational period.

Another object is to provide a group of relays with auxiliary apparatus in unitary structures which may be individual to a telephone line without the use of an excessive amount of common apparatus and with the use of only such common apparatus as is positive in operation and not interfering between the various lines connected to the system.

Other objects of my invention and the invention itself will be apparent as the description progresses. Referring to the drawings accompanying this specification Figure 1 shows the circuits and arrangement of the diagrammatical arrangement of the apparatus involved in a preferred embodiment of my invention.

Fig. 2 shows a side view of a relay selector switch mechanism embodying my invention.

Fig. 3 shows an end view of the device shown in Fig. 2.

Referring to Fig. 1 at A, I show a telephone substation located on a line L-1, terminating in central office line apparatus L-S. At H, I show a connector switch trunk circuit mechanism of the usual type, certain modifications and improvements being therein included however to more fully carry out the purposes of my invention.

At L-2, I show a called line upon which is located a telephone substation B, the called line likewise terminating in line switch ap-

paratus L.S. 2, a portion of which only is shown but the remaining portion not shown is understood to be the same as that shown at L.S. Although I show only one connector switch circuit at H, it is understood that in practice many would be employed, the incoming conductors of some of them being indicated at H-2, H-3, H-4, and H-5.

Relay line switch contacts for the different trunk circuits shown as indicated in the drawing and above referred to are indicated at 1-2-3 for the trunk circuit H-2; 4-5-6 for the trunk circuit H, the other sets of corresponding relay line switch contacts for the other trunk circuits being shown at C.S. 3, C.S. 4, and at C.S. 5. In the operation of the system it is understood that only one set of relay line switch contacts of a given line switch will be at any one time operated.

Small controlling magnets for the above sets of line switch contacts are shown at L.M. 1, L.M. 2, L.M. 3, L.M. 4 and L.M. 5. A similarly disposed and similarly operating magnet L.M. is arranged to control the set of contacts comprising contacts C-6, 12, 13, 14, 15 and 16. This line switch magnet L.M. and its controlled contacts become common to the relay line switch mechanism and common to the group of trunk switch magnets and their controlled contacts. A line relay L.R. and a controlling latch relay C.L. is provided for the line circuit and common to the group of line magnets above referred to.

At W-1 and W-2 I show 2 traveling switch wipers preferably rotatably mounted on a common shaft and having a number of operative positions corresponding to the number of trunk circuits, such as the trunk circuit H which are common to a group of lines served by the said trunk circuits. The wipers W-1 and W-2 are advanced from one operative position to another on the back stroke of the stepping magnet S.M.L. which stepping magnet is arranged to interrupt its own circuit when its armature is attracted. The circuit of the stepping magnet S.M.L. is carried through the wiper W-2 and the particular contact leading to a particular trunk circuit upon which contact the wiper W-2 at the time rests, the circuit arrangements in the trunk circuits such as H being such that an operative circuit for the stepping magnet

S.M.L. is accomplished whenever the switch wiper W—2 rests upon a contact of a busy trunk circuit to cause the stepping magnet to advance the wiper and its associated 5 wiper W—1 to the contacts of the next succeeding trunk circuit so that when the wipers finally come to rest they will rest upon contacts of an idle trunk circuit.

The wiper W—1 is provided for the purpose 10 of selecting the proper selective line magnet of a calling line circuit, to pre-select the trunk circuit such as the trunk circuit H, to extend a telephonic connection from the calling line such as L—1 to the called line 15 L—2. Terminals for a connection from a trunk circuit to the lines when they are called lines appear at 17 for the line L—1 and at 18, 19, 20 and 21 for the line L—2.

Referring to Figs. 2 and 3 at C.L. I show 20 a controlling latching magnet for the relay selector mechanism of my invention and at L.M. 1, L.M. 2, L.M. 3, L.M. 4 and L.M. 5, I show trunk circuit selector magnets for the relay selector and at L.M. I show a controlling 25 magnet for the relay selector whose purpose will be made apparent as the description progresses.

Armatures such as A—1, A—2, A—3, 30 A—4, A—5 and A—6 are provided for the group of magnets L.M. 1 to L.M. 5 inclusive, each armature being provided with a latch catch L.C.

In Fig. 3 portions of the armatures and associated parts including portions of magnets L.M. 3 and L.M. 4 for the said magnets are shown broken away to more clearly expose the operating latching magnet C.L. and portions of its armature A and associated contact spring set S.A. retractal spring S. 40 together with associated apparatus.

A set of contact springs C.S. 1, C.S. 2, C.S. 3, C.S. 4, C.S. 5 and C.S. 6 are provided for the armatures A—1 to A—6 inclusive and an additional set of contacts C—6 is 45 provided for the armature A—6 which contact set is operated whenever the said armature is attracted due to the energization of in controlling magnet L.M.

In order to carry out the purposes of my 50 invention the mechanism of the selector switch shown in Figs. 2 or 3 is so arranged that by causing the energization of any of the small magnets L.M. 1 to L.M. 5 inclusive to attract its associated armature and by 55 energizing the controlling latching magnet C.L. to attract its armature A that any one of the attracted armatures such as L.M. will have its latch catch L.C. latch on the end of the latching armature A so that upon a succeeding 60 deenergization of the magnet C.L. the latched armature will be lifted vertically, operating its associated set of springs such as for instance the set of springs C.S. 1. The previously energized selector magnet such as for instance the magnet L.M. 1 may now

be deenergized, the spring set as C.S. 1 remaining operated due to the retractal force of the spring S secured to the armature A which withdraws this armature to its normal position after having been attracted by 70 its operating magnet C.L. Now, whenever it is desired to release the operated spring set such as the spring set C.S. it is only necessary to cause a momentary operation of the magnet C.L. to unlatch the catch 75 member L.C. of the latched in armature.

To facilitate a better understanding of my invention a description of the embodiment illustrated will now be had, particular reference being made to figure 1, the description being made plainer if desired by reference to the other figures the same reference characters being used in all of the figures.

The subscriber A will initiate a call by 80 removing his receiver from the hook closing the line circuit of the line L—1 through a circuit interrupter D which may be the well known form of automatic calling dial and a substation talking apparatus shown in the 90 usual conventional form. Inclosure of the line circuit will thereupon operate the line relay L.R. through normal contacts 16 and 14, a source of current being included in this circuit and shown at B—1, the line relay 95 thereupon being energized will attract its armatures closing contacts in the circuits of the line switch magnets L.M. 1 to L.M. 5 inclusive but only one of these magnets will be energized, the particular one energized 100 depending upon the position of the switch wiper W—1 which completes the circuit of one of them in the position illustrated, this one being the magnet L.M. 2. Included in circuit with this selected line magnet L.M. 2 105 through contacts of the line relay L.R. and through the preselecting switch wiper W—1 is the line magnet L.M. common to the group of magnets L.M. 1 to L.M. 5, which magnet L.M. will operate at the same time 110 as magnet L.M. 2. The magnets L.M. and L.M. 2 being energized will attract their armatures conditioning their latch catches L.C. to be latched by the armature A of the controlling magnet C.L. after the controlling 115 magnet C.L. is energized. This now occurs, the controlling magnet C.L. being energized subsequent to the energization of the magnet L.M. since L.M. attracts its armature, closing contacts C—6 in the circuit of the controlling magnet C.L. together with a source of current. Current from the 120 said source will flow over this circuit which may be traced as follows. From the ground pole of battery through contacts C—6 of the magnet L.M. normal contacts 12 of the set associated with the magnet L.M. normal contacts S.A. and the winding of the controlling magnet C.L. to the negative pole of

the source of the current. This will cause 125 the magnet L.M. normal contacts 12 of the set associated with the magnet L.M. normal contacts S.A. and the winding of the controlling magnet C.L. to the negative pole of the source of the current. This will cause 130

the energization of the magnet C.L. which will attract its armature A and due to the opening of the contacts S.A. in its circuit, the magnet C.L. will immediately again release its armature A to lift the locked in armatures A-2 and A-6 whose latch catches L.C. are advanced to their latching position due to the attraction of their magnets L.M. and L.M. 2 upon the armatures 5 A-2 and A-6 and will operate the spring sets C-S 2 and C.S. 6. The spring set C.S. 6 being operated will cause the breaking of contacts 12 which will open the circuit of the magnet C.L. so that it will not again be 10 operated unless perchance the latch catch L.C. of the attracted armature A-6 was not at the first effort, latched, in which case the action would be repeated.

At the same time that the contacts 12 20 were opened other contacts of the set of contacts C.S. 6 were also operated. The contacts 14 and 16 are to perform the same function as the break contacts of the conventional line cut off relay of the art, 25 namely, to disassociate the line relay and all connections to ground from the line talking conductors.

Contacts 13 are closed to provide a release circuit for the line switch as will be made 30 later apparent as the narrative progresses.

The set of contacts comprising contact pairs 15 and 115 are operated to make the multiplied connector contacts 17 of the line test busy, should a call be made by some 35 other station of the system for the line L-1. The method by which this is accomplished will later be made apparent but for the present it is sufficient to state that the third connector contact of the set 17 counting 40 from the top, called the test contact by the operation of this set of contacts is connected to ground through the contacts 115 which are now closed and the connection to battery through the line magnet L.M. is removed from the said test contact.

At the same time that the spring contact set C.S. 6 was operated the spring contact set C.S. 2 was also operated, closing contact pairs 5 and 6 to extend the line conductors 50 of the line L-1 to the talking strands, 22 and 23 of the trunk circuit H, which trunk circuit is herein illustrated as being a connector switch trunk circuit, in which the outgoing conductors are connected to travelling switch contacts directly operated under the control of the calling subscriber's dial. The pair of contacts 4 being closed will extend the release circuit which includes the winding of the controlling magnet C.L. 60 of the calling line circuit through now closed contacts 13, of the contact set C.S. 6 and the contacts 4 to normally opened contacts of a release relay R.L. of the trunk circuit H which normally opened contacts 65 at this time remain open since, and will so

remain until the end of the connective period.

The talking strands of the line circuit L-1 are extended through now closed contact pairs 4 and 5 of the set C.S. 2 to the 70 talking strands 22 and 23 of the connector switch circuit and the subscriber's instrument remaining across the talking strands of the line circuit will complete a circuit including the said subscriber's instrument and the source of current over the strands 22 and 23 of the connector switch, an impedance battery feed coil 24 and the impulse relay winding 25 connected to ground and the negative pole of battery respectively. Current flowing through the impulse relay winding will cause the relay to attract its armatures closing contacts 26 and 27 and opening contacts 28 for purposes which will appear.

The contacts 27 being closed will complete a circuit including the source of current for the slow releasing interval relay S.R.I., the circuit being traced from the ground pole of battery through the contacts 27, winding of the relay S.R.I. through 90 the first position contacts of the side switch wiper 29 to the negative pole of battery.

The slow releasing impulse relay S.R.I. will thereby attract its armatures, closing 95 contacts 30 and 31 and opening contacts 32 for purposes which will later appear. The closure of the contacts 26 and of the contacts 30 of the relays 25 and S.R.I. both place a ground connection upon the circuit conductor 33 leading to the contact 34 of the preselection switch wiper W-2 which at the time is resting upon the said contact 34 and the ground connection being applied will complete a circuit for the stepping magnet S.M.L. for the preselection switch to cause the preselection switch wipers W-1 and W-2 to advance to their next resting position whereupon they will make contact with circuit conductors 35 and 36 which are 100 associated with the trunk circuit H-3 to preselect trunk H-3 for a succeeding call.

The wiper W-1 leaving the contact 37 will remove the ground connection from the selector magnets, such as the selector magnet L.M. 2 which selector magnets are associated with the trunk circuit H so that on a succeeding call by another line, the magnet L.M. 2 associated with the trunk circuit H and with the said calling line, will not be 115 operated but instead on the next succeeding call by a calling line, the magnet L.M. 3 of the trunk circuit H-3 will be operated.

If the trunk circuit H-3 were at the time in use, due to its previously having been 125 seized by another calling line circuit, the preselector switch wipers would advance another step to the contacts 38 and 39 since the stepping magnet S.M.L. would have its circuit reestablished by an existing busy 130

ground potential upon the contact 35 of the assumed busy trunk circuit H-3 so that the preselector switch wipers will advance from trunk point to trunk point until they finally 5 come to rest upon the contacts of an idle trunk circuit.

The trunk connector switch circuits are now conditioned for the dialing operation by the subscriber by means of which the subscriber 10 can control the movement of the traveling switch contacts of the connector switch H to cause them to make connection with contacts connected to the called desired line terminals. The subscriber now by 15 operating his dial to a degree determined by the first digital designation of the called line number will interrupt the circuit of the line L-1 a predetermined number of times depending upon the degree of operation of 20 the dial.

Upon the first opening of the line circuit by the calling subscriber's dial, the contacts 27 will be momentarily opened and the contacts 28 momentarily closed, the armature 25 vibrating rapidly back to its operated position, the process being repeated rapidly a predetermined number of times in accordance with the number of times the line circuit is opened by the calling subscriber's 30 dial.

The relay S.R.I. will remain energized during this period since it is of the well-known slow releasing type and only allows its armatures to be retracted slowly. Upon 35 the first retraction of the armatures of the relay 25, a circuit is closed for the slow releasing relay S.R.R., the circuit being traced from the ground pole of battery to the normal contacts 28 of the impulse relay 25 through now made contacts 31 of the relay 40 S.R.I. which maintains its armatures attracted during this period through the winding of the relay S.R.R. and through the winding of the primary stepping magnets P.M. of the connector switch through first 45 position contacts of the side switch wiper 40 to the negative pole of the source of current. This circuit is closed once for every time that the line is opened during the sending 50 of the first series of impulses by the calling subscriber and for each opening of the line circuit entailing a consequent closing of this traced circuit, the primary stepping magnet P.M. is operated and advances the 55 connector switch wipers C.W. one vertical step to directly locate a particular level of contacts in which level contacts of the called for line are located.

The slow releasing relay S.R.R. was 60 operated on the first opening of the line circuit by the flow of current over the circuit just traced and being of the slow releasing type maintained its armature attracted throughout the series of line circuit 65 interruptions. At ESC, I show an escape

magnet controlling the operation of the side switch wipers in the well-known way and the mechanical arrangement is such that whenever an escape magnet is energized and thereafter deenergized that upon 70 such deenergization of the escape magnet the side switch wipers will be advanced to their next contact making position.

When the relay S.R.R. attracted its armature it completed a circuit for the escape 75 magnet ESC, the circuit including the source of current, the circuit being traced as follows. From the ground pole of the battery through normally opened contacts 41 of the relay S.R.R. through the winding 80 of the escape magnet E.S.C. a resistance coil R.E.S. to the negative pole of the source of current. This will cause the energization of the escape magnet and upon the release of the armature of the relay S.R.R. 85 which occurs immediately after the subscriber's dial has come to rest, the escape magnet will advance its wipers to their second operative position. This release of the armature of the relay S.R.R. occurs 90 since at the end of the series of circuit interruptions the relay 25 will cause its armatures to be steadily attracted, thus steadily interrupting for a sufficient length of time contacts 28 in the circuit of the slow releasing relay S.R.R. which will have time to release its armature and thereby cause the opening of the contacts 41 in the circuit of the escape magnet.

All of the side switch wipers are now in 100 second position. The subscriber will thereafter again operate his dial causing a second series of interruptions of the line circuit and the relays 25 S.R.I. and S.R.R. operating as before, the same results will be 105 obtained except that the side switch wipers being in second position, the winding of the secondary stepping magnet S.M. is substituted in the stepping circuit which includes the slow releasing relay S.R.R. and the secondary stepping magnet S.M. will advance the connector switch traveling contacts along the previously selected level of contacts to directly locate the contacts belonging to the called for line. At the end 115 of the second series of circuit interruptions the escape magnet will in the same manner as before described for advancing the side switch wipers from first to second position, will now advance the side switch wipers 120 from second to third position. This will occur if the called for line upon whose contacts the connector switch wipers have come to rest is idle or unengaged. The narrative will be continued for the present 125 with the assumption that the called for line is idle and therefore selectable.

In the third position of side switch wiper 42 encounters ground and thereby closes a circuit including the source of current for 130

line magnet L.M. of the called line which thereupon will be energized attracting its armature, closing contacts C—6. The contacts C—6 being closed a circuit will be completed for the controlling operating magnet C.L. of the called line L—2, the circuit being traced from the ground pole of battery through normally opened contacts C—6 of the line magnet L.M., normally closed contacts 43 of the set of springs located in the drawing to the left of, and under the control of the line magnet L.M., normal contacts 44 and the winding of the controlling magnet C.L. to the negative pole of the source of current. Current flowing over this circuit will energize the controlling magnet C.L.

The escape magnet is also energized when the side switch wipers reach third position, the energizing circuit being traced from the ground pole of battery through normal contacts 51 of the release magnet R.L., third position contact and wiper 52 of the side switch, the winding of the escape magnet, the resistance coil R.E.S. to the negative pole of the source of current. The energization of the escape magnet will prepare the side switch wipers to advance into fourth position upon the later deenergization of the escape magnet as will later appear. The controlling magnet C.L. of the called line switch circuit L.S. 2 will interrupt its own circuit at 44 in the manner previously described for the like magnet of the calling line and the armature of the controlling magnet C.L. will thereupon be retracted to latch in the armature of the magnet L.M. to operate the set of springs associated therewith and shown to the left thereof. When this is done the contacts 43, 45, 46 and 47 will be open and the contacts 49, 50 and 53 will be closed. The contacts 43 being open will open the circuit of the latching magnet C.L.

The closing of the contacts 53 perform no function when the line is a called line. The opening of the contacts 45 opens the circuit of the line relay L.R. to remove it from the line strands. The closure of the contacts 50 extends the severed line strand to a talking conductor 54. The breaking of the contacts 46 opens the above described energizing circuit for the line magnet L.M. and places ground potential of the contact 20 of the connector switch. The breaking of the contacts 47 removes the ground connection from the other talking strand. The line strands now being extended through the line switch circuit to the connector circuit the ringing of the called subscriber's station will now commence, the ringing circuit being traced as follows:—from ground through third position contact and wiper 61 connector switch wiper and contact 18, one side of the line L—2 through the sub-

scriber's telephone bell 62, the other side of the line, now closed line switch contacts 50, through connector switch contacts 19 and wiper resting thereon through side switch wiper 63 and third position contact thereof 70 through the winding of the ringing trip magnet 64 resistance lamp 65 and then alternately through the interrupter mechanism 66 to negative battery or through ringing generator 67 to negative battery. The ringing will now continue until subscriber at B responds by taking his receiver from the hook and making a conductive bridge to direct current across the line L—2 which will cause the operation of the ringing trip magnet 64 to close the contacts 68 thereof. The contacts 68 being closed will short circuit winding of the escape magnet E.S.C. to cause it to release the side switch wipers which will advance into fourth position thus 85 opening the ringing circuit just described and extending the talking conductors of the called line through fourth position contacts of side switch wipers 61 and 63 to the talking strands 22 and 23 of the connector 90 switch circuit.

The usual impedance battery feed coils are shown connected to the called end of the talking strands of the connector switch circuit, through which battery current is supplied to the called substation transmitter at B. Side switch wiper 52 advancing into fourth position opens the circuit of the escape magnet E.S.C. so that it will not be reenergized after the contacts 68 are opened 100 as will now occur. The wiper 42 of the third and fourth position connects ground to the third wiper of the connector switch and thereby to the multiplied contacts of the line in the different connector switches of 105 the group so that the line may not be seized by other connector switches.

The wiper 69 in fourth position conditions the release circuit for the line switch L.S. 2 as will be described later. The side switch wiper 29 in advancing from third to fourth position opens the circuit of the slow releasing relay S.R.I. and short circuits a second winding placed upon the impulse relay 25. This for the purpose of making impulse battery relay 25 slow releasing so that the release of the connector switch H may not be accomplished by a momentary opening of the calling line circuit such as might be occasioned by accidental operation of the 110 calling subscriber's dial at D.

The subscribers are now in conversational circuit and it will be seen that at this time no current is flowing throughout the system involved in this connection except the talking current for feeding the substation transmitters, this talking current in the case of the calling subscriber holding the relay 25 operated. When the conversational period is over, the calling subscriber will replace his 115 120 125 130

receiver to the hook breaking the circuit of the line L-1 to release the relay 25 in circuit with the line. When this relay is released a circuit is completed through off 5 normal contacts O.N. for the release magnet R.L. The circuit being traced from the ground pole of battery through normal contacts 28 of the relay 25, normal contacts 32 of the relay S.R.I. through off normal contacts O.N. of the switch through the winding of the release magnet R.L. to the negative pole of battery.

The release magnet will attract its armatures opening the contacts 51 and closing 15 contacts 70, 71 and 72. The contacts 72 being closed will produce a locking circuit for the release magnet R.L. including off normal contacts O.N., this to insure that the release magnet may remain energized 20 until the switch mechanism has been fully restored to its normal position. The contacts 70 and 71 being closed, ground is connected through the said contacts to the controlling magnet C.L. of the two connected 25 line circuits, to momentarily operate these controlling magnets, to release the latched in armatures.

Completed circuit for the magnet C.L. of the calling line L-1 may be traced from 30 the negative pole of battery through the winding of the magnet C.L. through now closed contacts 13 of the calling line switch, now closed contacts 4 of the set of contacts C.S. 2 through the now closed contacts 71 35 of the release magnet R.L. to the ground pole of the source of current. Current from the said source will energize the magnet C.L. which will immediately attract its armature to unlatch any latched in armatures, and in the case being described the armature A-2 of the magnet L.M. 2 and the armature A-6 of the magnet L.M. so that the sets of springs controlled thereby, namely, the set C.S. 2 and the set C.S. 6 40 will be restored to their normal positions. Likewise will the controlling magnet C.L. of the called line circuit be energized, its energizing circuit being traced from the negative pole of battery through its winding, connector switch contacts 21 and connector switch wiper 48, side switch wiper 69 and fourth position contact thereof now closed contact 70 of the release magnet R.L. to the ground pole of the source of current. 45 The magnet C.L. being energized will unlatch the armature A-6 of the called line switch which controls the set of springs shown to the left of the magnet L.M. of the called line which magnet in the first place 50 controlled the latching of the armature A-6. This set of springs will also be restored to normal position therefore in the case of the called line and the connector switch mechanism being restored to normal, 55 the apparatus involved in the preceding de-

scribed connection may be again used to complete another connection.

Reverting now to that point of the description where the assumption was made that the called for line was idle and therefore selectable, let us assume that the called for line was busy in which case the system is arranged to give a busy signal to the calling subscriber and to prevent a connection being made with the busy line whereupon 75 the called subscriber may release the connection by restoring his receiver to the hook.

The above functions are performed as follows, the side switch wipers at this stage of the operation being in second position as 80 before described. If the called for line is busy this will be evidenced by ground potential being placed upon the test contact such as the test contact 20 thereof, either by the closing of contacts 49 of the called line 85 switch springs or by ground being placed upon the said contact 20 through the wiper of the connector switch engaging a multiple of the contact 20, the ground being applied through third or fourth position contacts of 90 a side switch wiper such as the side switch wiper 42 illustrated for the connector switch H. When such a guarding ground is encountered upon the contact 20 a circuit is completed for the test relay T.R. of the connector switch circuit through second position contact of the side switch wiper 42. To operate the test relay T.R. and to maintain the escape magnet E.S.C. energized the serial circuit for the escape magnet and the 95 test relay T.R. which is thereby formed may be traced as follows. From the guarding ground upon the test contact 20 of the called for line through the third wiper of the connector switch engaging the said contact 100 through second position contact and wiper 42 of the side switch, normal contacts 73 and the winding of the test relay T.R., normal contacts 74 of the relay S.R.R., the winding of the escape magnet E.S.C. to 110 the negative pole of the source of current through the resistance coil R.E.S. Thus the escape magnet is maintained energized to prevent it allowing the side switch wipers to escape into third position.

Test relay T.R. attracting its armatures will provide a locking circuit for the test relay winding and the escape magnet winding by the closure of contacts 75, the said circuit leading through the contacts 75 and 120 off normal contacts to ground.

The circuit of the secondary stepping magnet S.M. is broken by the opening of contacts 76 of the relay T.R. so that any subsequent operation of the subscriber's dial or short interruption of the line circuit will not operate the stepping magnet. The closure of the contacts 77 of the relay T.R. connects a busy tone current to a talking strand of the connector switch circuit in the 125 130

usual way. The subscriber hearing the busy tone will know that the called for line is busy and will thereupon retire his talking set from the line circuit, thus opening the line and causing the release of the connector switch and calling line switch in the manner previously described.

It is to be understood that in illustrating and describing a particular embodiment of my invention that numerous and extensive departures may be made from the same without departing from the spirit thereof and that where I have illustrated the device *per se* as applied to a particular system in a particular manner of use that it is by no means limited to such a system since other uses will readily be apparent to those skilled in the art to which my invention appertains.

20 What I claim as my invention is:—

1. In a telephone system, the combination with a plurality of telephone lines, a relay mechanism for each of the lines for making connections with other telephone lines, a set 25 of contact springs for the said relay mechanism for each of the other telephone lines adapted when operated to interconnect the said other telephone lines with one of the said telephone lines, an electromagnet for 30 each of the said contact sets, a controlling magnet for the said relay mechanism, means to select one of the said contact sets upon the conjoint energization of the said controlling magnet and one of the said electromagnets and means to deenergize the said controlling magnet to cause the said contact set to be operated.

2. In a telephone system, the combination with a plurality of telephone lines, a relay 40 mechanism for each of the lines for making connections with other telephone lines, a set of contact springs for the said relay mechanism for each of the other telephone lines adapted when operated to interconnect one 45 of the said other telephone lines with the said telephone line, an electromagnet for each of the said contact sets, a controlling magnet for the said relay mechanism, means to select one of the said contact sets upon 50 the conjoint energization of the said controlling magnet and one of the said electromagnets, means to deenergize the said controlling magnet to cause the said contact set to be operated, and means to release the said 55 contact set upon a subsequent energization of the said controlling magnet.

3. In a telephone system, a calling and a called telephone line, substations on the said lines, circuit interrupters at the said 60 substations, and a main station in which the said lines terminate, a directly operated switch at the main station adapted to be operated under the control of a substation circuit interrupter to interconnect the calling 65 telephone line with the called telephone line,

an impulse relay associated with said switch having an armature adapted to vibrate in unison with the said circuit interruptions to control the operation of the said switch, release mechanism for the said switch and controlling means independent of the called line 70 substation for the said impulse relay to cause the impulse relay to be slow releasing after the said impulse relay has controlled the directive operation of the said switch and circuit connections thereafter operative when the calling substation retires to cause the said impulse relay to retract its armature to 75 operate the said release mechanism.

4. In a telephone system a plurality of 80 telephone lines, a line switch for each of the said lines, a plurality of trunk circuits for the said telephone lines, each trunk circuit terminating in multiple contacts on each of the said line switches, multiplied non- 85 traveling contacts for each of the said line switches, said last named multiple contacts being terminals of the associated telephone line, a set of line circuit terminals being adapted to be interconnected with a set of 90 trunk circuit terminals, a controlling magnet for the said line switch, a selective electromagnet to select for interconnection a set of the said line circuit terminals and the co-operating set of trunk circuit terminals, 95 means to simultaneously energize the said controlling magnet and one of the said selective electromagnets, means to subsequently deenergize the said controlling magnet, and means responsive to the said deenergization to cause the interconnection of the selected connected contact sets. 100

5. In a telephone system a plurality of telephone lines, a line switch for each of the said lines, a plurality of trunk circuits for 105 the said telephone lines, each trunk circuit terminating in multiplied contacts on each of the said line switches, multiplied non-traveling contacts for each of the said line switches, said last named multiple contacts 110 being terminals of the associated telephone line, a set of line circuit terminals being adapted to be interconnected with a set of trunk circuit terminals, a controlling magnet for the said line switch, a selective electromagnet to select for interconnection a set of the said line circuit terminals and the co-operating set of trunk circuit terminals, means to simultaneously energize the said controlling magnet and one of the said 115 selective electromagnets, means to subsequently deenergize the said controlling magnet means responsive to the said deenergization to cause the interconnection of the selected connected contact sets and means to 120 cause the release of the selectively operated contact set upon a subsequent reenergization of the controlling electromagnet. 125

6. In a telephone system a plurality of telephone lines, a line switch for each of the 130

said lines, a plurality of trunk circuits for the said telephone lines, each trunk circuit terminating in multipled contacts on each of the said line switches, multipled non-traveling contacts for each of the said line switches, said last named multipled contacts being terminals of the associated telephone line, a set of line circuit terminals being adapted to be interconnected with a set of 10 trunk circuit terminals, a controlling magnet for the said line switch, a selective electromagnetic to select for interconnection a set of the said line circuit terminals and the coöperating set of trunk circuit terminals, means 15 to simultaneously energize the said controlling magnet and one of the said selective electromagnets, means to subsequently de-energize the said controlling magnet, means responsive to the said deenergization to 20 cause the interconnection of the selected connected contact sets, means to cause the release of the selectively operated contact set upon a subsequent reënergization controlling electromagnet, and a pair of contacts 25 included in the energizing circuit of the said controlling electromagnet to break the said energizing circuit whenever the controlling magnet is energized.

7. In a system for selection, a common elec- 30 troresponsive motor device, a plurality of circuits therefor, contact terminals for the said circuits and a stationary connective device for interconnecting one of the said circuits with selected other of the said cir- 35 cuits, means operating under the conjoint action of said common electroresponsive motor device and one of the said stationary connective devices to mechanically latch a set of said contact terminals of the said cir- 40 cuit in connection with the said selected other circuit, and an unlatching means responsive to a subsequent energization of the said common device to restore the said contact terminals.

45 8. In a telephone system a plurality of telephone lines, a group of trunk lines for extending the circuit from the said telephone lines to other telephone lines, a line switch for each of the said lines, means to 50 cause the line switch of the calling telephone line to interconnect the said calling telephone line to an idle one of the said trunk circuits, mechanical means to maintain the said connection and electrical means for re- 55 leasing the said connection.

9. In a telephone system in combination with a plurality of telephone lines, a line switch for each of the lines, a group of trunk lines for extending the circuit of the line 60 conductors of the said telephone lines, electrical means to operate the said line switch to connect its associated telephone line when calling, with an idle one of the said trunk circuits, mechanical latching means to main- 65 tain the said connection, an automatic means

to disestablish the said connection upon a subsequent reënergization of the said electrical means.

10. In a telephone system, a telephone line, a line switch therefor, a group of the 70 lines each having contact terminals in the said line switch, coöperating contact terminals for each of the first named contact terminal sets, said last named terminals being connected to circuit conductors of the 75 first named line, electromagnetic means initially operated by line apparatus of the said line to interconnect a set of the said first named line contact terminals to a set of contact terminals connected to an idle one 80 of the said group of lines and means to cause the release of an established connection by a subsequent energization of a portion of the said electromagnetic means.

11. In combination with an automatic 85 telephone switch mechanism, calling and called sub-station apparatus adapted to be inter-connected by the said mechanism, an impulse relay to control setting-up operation of the said mechanism under the control of the said calling sub-station apparatus, the said impulse relay being of the fast operating type, and means responsive to the setting-up of the said switch mechanism to make the said relay of a slow operating type, a release magnet for the said switch mechanism, said release mechanism being under the control of the said impulse relay.

12. In a telephone system, telephone lines, 100 relay mechanism for establishing connections between said lines, electromagnets and electrical contacts for the said relay mechanism, substation apparatus on the telephone lines, a pair of talking conductors for each 105 of the said telephone lines leading from the said substation apparatus to the said relay mechanism, means operated under the control of the said substation apparatus over the said pair of talking conductors to cause 110 a pair of electromagnets of the said relay mechanism to be energized to operate selected relay contacts to connect an associated telephone line with another of the said telephone lines, and a mechanical means 115 common to all of the said relay contacts for locking the said relay contacts in their operated position.

13. In a telephone system, telephone sub- 120 stations, telephone lines for the said sub- stations, each telephone line comprising a single pair of wires, relays controlled over the said pair of wires for establishing connections between a substation on a calling line and a substation on a called line, a me- 125 chanical means common to a group of the said relays for holding the said relays in their contact operating position.

14. In a telephone system, telephone sub- 130 stations, telephone lines for the said sub-

stations, each telephone line comprising a single pair of wires, relays controlled over the said pair of wires for establishing connections between a substation on a calling line and a substation on a called line, a mechanical means common to a group of the said relays for holding the said relays in their contact operating position and automatic means for restoring an operated set 10 of relay contacts.

15. In a telephone system, telephone sub-stations, telephone lines for the said sub-stations, each telephone line comprising a single pair of wires, relays controlled over the said pair of wires for establishing connections between a substation on a calling line and a substation on a called line, a mechanical means common to a group of the said relays for holding the said relays 20 in their contact operating position and automatic means for restoring an operated set of relay contacts, the said automatic means being under the control of the said substation over the said pair of wires.

25. 16. In a selector switch a plurality of sets of selector contacts, individual operating means for each set, a selective controlling magnet for each individual operating means, a common controlling magnet 30 and means operative responsive to the joint energization of the said common mag-

net and one of the selective magnets to operate a selected contact set.

17. In a selector switch a plurality of sets of selector contacts, individual operating means for each set, a selective controlling magnet for each individual operating means, a common controlling magnet and means operative responsive to the joint energization of the said common magnet 35 and one of the selective magnets to operate a selected contact set and means responsive to a subsequent energization of the said common magnet alone to restore operated contact set. 40

18. In combination with an automatic telephone switch mechanism, calling and called sub-station apparatus adapted to be inter-connected by the said mechanism, an impulse relay to control setting-up operation of the said mechanism under the control of the said calling sub-station apparatus, the said impulse relay being of the fast operating type, and means responsive to the setting-up of the said switch mechanism to make the said relay of a slow operating type. 45

In witness whereof, I hereunto subscribe my name this 10th day of August, A. D. 1918.

FRANK M. SLOUGH.
